WILLIAM A. KNIGHT AND LEO BAUER, OF NEWARK, NEW JERSEY.

HAT-SWEAT-SEWING MACHINE.

1,138,669.

Specification of Letters Patent.

Patented May 11, 1915.

Application filed April 9, 1913. Serial No. 759,927.

To all whom it may concern:

Be it known that we, WILLIAM A. KNIGHT and LEO BAUER, each a citizen of the United States, and each residing in the city of Newark, county of Essex, and State of New Jersey, have jointly invented a certain new and useful Improvement in Hat-Sweat-Sewing Machines, of which the following is a specification.

- 10 Our invention is concerned with machines for sewing sweat bands or leathers, commonly called "sweats," in hats, and it is intended more especially for sewing sweat bands in soft or felt hats, and is designed 15 to eliminate numerous defects heretofore present in apparatus of this character.
- It has been customary heretofore in feeding the hat forward while the sweat band is 20 being sewed in place, to make use of a corrugated wheel, which contacts with the outer surface of the hat and usually bears against the band or ribbon or other trimming material, which is applied to the hat to afford a finish at the lower portion of the crown 25 adjacent to the rim. The application of the feeding means in this neighborhood frequently results in marking the ribbon or the upper surface of the rim in an objectionable manner and it is not uncommon for the ribbon to be torn and the hat ruined by the 30 feed being so applied. With a sewing machine constructed in accordance with our invention this objectionable feature is not present, as the feed is applied, not to the outer surface of the crown or to the upper 35 surface of the rim, but it is applied on the lower surface of the hat rim next to the edge of the sweat band and, while a machine constructed in accordance with our invention 40 is not likely to leave feed marks on the hat, if it should happen that the hat is marked in sewing the sweat band therein, the marks will not be noticeable, as such marks as appear will be on the under surface 45 of the rim next to the edge of the sweat band where they will not be likely to be observed.

Another feature of our invention resides in making provision for holding the hat firmly and securely in place while the sweat band is being sewed therein. Sewing a sweat band in a hat is a delicate operation, as it must be blind sewed and the stitches must not penetrate through the material of the hat so as to be visible from above, and

at the same time the stitches must penetrate sufficiently to secure the sweat band firmly in place so it will not come loose or be readily detached. According to our invention the same means which is made use of for feeding the hat and which, as already stated, is applied to the under surface of the rim near the sweat band, also serves as a means for pressing and holding it firmly in place during the sewing operation.

Another feature of our invention consists in the provision of a movable support for the hat during the sewing operation, this support being free to move with the hat, instead of being fixed, so that it is not necessary as heretofore to move the hat along over a fixed and immovable support and this results in it being possible to perform the feeding operation more easily and to lessen the necessary force and pressure used for feeding, thereby decreasing the liability of damage to the hat from pressure applied in feeding it in the machine during the sewing operation.

Another feature of our invention resides in the provision of an improved tension apparatus to prevent the tearing of sweat bands, which are of soft leather, by the thread in the sewing operation. In accordance with customary usage we make use of a chain stitch for sewing the sweat band in place. The edge of the sweat leather and a portion of the under surface of the hat rim adjacent thereto, where the hat is bent over to form the junction between the crown and rim, are "whipped" together, the needle passing partially through the material of the hat at the bend and through the edge of the sweat leather and the thread being drawn back in a loop over the exposed edges, through which loop the needle passes on its next forward movement, to form the chain stitch. A cord is preferably sewed in between the edge of the sweat band and the material of the hat, although this may be omitted, of course, if desired. A looper is made use of for drawing a loop in the thread after the needle has passed through the parts to be sewed together and, as the thread has to be drawn out into a fairly long loop in order to provide sufficient length of thread for the whipping operation, a considerable pull is exerted by the thread when the loop is formed and this, according to the present practice, frequently results in

tearing the soft material of the sweat leather, and if the tension on the thread is sufficiently loosened to prevent this effect being produced, the thread is likely to become 5 snarled and stop the machine or spoil the hat. In order to take care of this situation, we have provided positive mechanical means for drawing off from the spool a sufficient length of thread for forming the loop and 10 for releasing the tension upon this extra length of thread as it is needed for making the loop and also for drawing up the thread after the loop is formed and the needle has passed through it to form the next stitch, so 15 that, while sufficient length of thread will always be available for forming the loop without tearing the sweat band or other parts being sewed, the thread after the loop has been formed and the next stitch produced will be drawn up so as to make the 20 stitching of the proper snugness.

Other objects of our invention will appear in the course of the specification and be pointed out in the claims, and with the foregoing and related objects in view, our invention 25 consists in the parts, improvements and combinations hereinafter set forth and claimed.

While we have illustrated and shall describe a specific form of construction, it is to be understood that the same is for the purpose of illustration only, and that our invention is not confined thereto, but is as broad as our claims, and that numerous 35 changes may be made in the construction illustrated without departing from the principle thereof or sacrificing the advantages of our invention.

In the drawings forming a part of this 40 specification and wherein the same reference characters are used to designate the same parts throughout, Figure 1 is a side elevational view of one form of machine embodying our invention; Fig. 2 is a sectional detail view taken partly in section on the line 2—2, Fig. 1; Fig. 3 is a plan view of the machine shown in Fig. 1; Fig. 4 is a detail cross sectional view taken on the line 4—4, Fig. 3 and showing the guiding mechanism; Fig. 5 45 is a longitudinal sectional view taken on the line 5—5, Fig. 3; Fig. 6 is a side elevational view of the main driving shaft of the machine and showing the cams and stops thereon; Fig. 7 is a detail cross sectional view on the line 7—7, Fig. 6; Fig. 8 is a transverse cross sectional view taken on the line 8—8, Fig. 3; and Figs. 9, 10, 11 and 12 are diagrammatical detail views showing the positions of the tension mechanism with respect 55 to the stitch forming mechanism.

Reference numeral 1 is applied to the frame of the machine, which may take any convenient form, but which is preferably constructed as a closed casing for inclosing 60 the moving parts so far as possible. A

main drive shaft 2 passes through the frame or casing 1 and is driven from any convenient source of power, as for example by a belt applied to the pulley 3, and this shaft 2 is further provided with one or more fly 70 wheels 4 which may be rounded so as to be conveniently grasped by the hand of the operator, as upon starting the machine or moving it slowly by hand if occasion should arise for such attention.

Our present invention is not directly concerned with the construction of the stitch forming mechanism and we may make use of any construction for this purpose. We have illustrated a form of stitch forming mechanism, commonly in use in various machines, such as fur sewing machines for instance, and which may conveniently be made use of for our purposes, and this portion of the machine as illustrated may be described 80 somewhat briefly.

The needle bar 5 is actuated from the drive shaft 2 by means of an eccentric 6 on the shaft 2 working in a yoke 7 attached to the needle bar 5. The looper bar 8, which carries or terminates in the looper 9, comprising the rounded heel extension 9^a and the loop entering point 9^b, is mounted on the shaft 10, which is rotatably received in a frame 11, which frame is pivoted at 12 to a carriage 13, slidable in the machine frame, and which is reciprocated by an eccentric 14 on the main drive shaft 2, working in a yoke 14^a which is secured to the carriage 13. The frame 11 is moved up and down on its pivots 12 by a toggle system comprising a bell-crank lever having arms 15 and 16 pivoted on the frame at 17, the arm 15 being connected to a link 18 which has secured thereto a strap 20 for the eccentric 19 also mounted on the drive shaft 2, and the opposite arm 16 of the bell-crank lever is connected by the link 21 to the pivoted frame 11 and is pivoted thereto at 22. With this arrangement the link 21 and the arm 16 of the bell-crank lever comprise a toggle, which acts to raise and lower the frame 11, and the looper bar 8 borne thereby, twice in every revolution of the drive shaft 2. The shaft 10 bearing the looper bar 8 is rocked in its bearings in the frame 11 by means of the arm 23 secured to the shaft 10 and having a ball 24 fitting in the cam slot 25 in the rocking cam piece 26, which is pivoted to the frame at 27, and is rocked on its pivot from an eccentric 27^a on the drive shaft 2 by means of a link 28 pivoted to the cam piece 26 at 28^a and provided with a suitable opening for receiving the eccentric 27^a on the main shaft 2.

The feed of the machine operates on the 125 shaft 29 which extends substantially vertically at one side of the frame or casing 1 and is given suitable bearings therein and it is operated from an eccentric 29^a on the main shaft by means of the link 30 provided with 130

an eccentric strap fitting over the eccentric 29^a on the drive shaft and the lever 31 pivoted to the frame and to which said link 30 is pivotally attached, link 32, pivotally connected to the lever 31, and the step-by-step feed 33 of the ordinary type and having a spring 34 attached thereto. This feed mechanism may be adjusted in any convenient and well known manner and operates to rotate the shaft 29 intermittently through a small angle as each stitch is formed and as will be readily understood.

The parts so far referred to being of any usual or desirable construction and operating in the usual manner to sew a chain stitch seam and to provide the necessary feed therefor need not be further described.

Coming now to the features of the machine illustrated which are original with us, 20 H is a hat, S the sweat band or leather to be sewed therein and C the cord which is preferably sewed in with the leather S but which may be omitted if desired.

The means for supporting the hat during the sewing operation comprise a ring 35 for extending entirely around the hat, and provided with a substantially cylindrical central opening, in which the crown of the hat is received, and with an outer downwardly tapering surface 36, on which the rim of the hat rests during the sewing operation. The ring 35 is provided with a recess or groove 37 extending entirely around its lower side and forming a track-way by which it rests on the rollers 38 which are rotatably supported in a frame 39, also preferably of ring shape, and the ring 35 is free to turn on the rollers 38 during the sewing operation and may be turned thereon 40 without appreciable friction. The frame 39 is carried on a leg or legs 40 which are free to swing on a pivot or pivots 41 and the entire hat carrying frame may be adjusted vertically on the machine frame or casing as by means of the screw 42 which operates to raise or lower the frame 39 by turning the sub-frame 43, to which the legs 40 are directly pivoted, on its pivots 44. A spring 44^a shown as a leaf spring, but which may be of any convenient form, serves to partially support the frame 39 and to prevent it from falling forward on the pivots 41 when the parts are separated as in removing a hat after it has been sewed.

55 The feed shaft 29 heretofore referred to is provided at its upper end with the feed wheel 45 which is formed with a corrugated feeding surface on its lower side, having substantially the form of the frustum of an inverted cone, and which resting upon the rim of the hat H and in contact with the underside thereof (turned upward in the sewing operation) holds it firmly in place on the supporting ring 35 and operates to advance the hat the necessary distance as

each stitch is completed, in readiness for receiving the next stitch. Means are also provided for holding the hat and its supporting means firmly in place in contact with the feed wheel 45 during the sewing operation, and in the construction shown this means comprises an idler or presser wheel 46 which is borne by the crooked arm 47 pivoted at 48 to an upstanding rod or post 49, which is mounted in any suitable manner so as to be movable substantially parallel to itself thus permitting the wheel 46 to be moved straight toward and away from the feed wheel 45. As shown, this substantially parallel bodily movement of the rod or post 49 is secured by attaching to the rod or post 49 a rigid horizontal extension 50 and supporting it on links 51 and 52, pivoted respectively to the member 50 and to the machine frame. A spring 53 serves to retract the parts just described, thereby holding the post normally close to the frame or casing 1 and securing a firm contact of the presser or idler wheel 46 with the inside of the hat, supporting the framework in which the hat rests and holding the supporting member 35 and the hat itself resting thereon firmly against the feed wheel 45. Other means than those described may, of course, be resorted to for the purposes 95 named. A latch 53^a of any convenient form is secured to an extension 54 on the post 49 and holds the arm 47 and wheel 46 down firmly in place when the latter has been adjusted in position.

100 The means for controlling the tension, in order to successfully meet the requirements of sewing sweat bands into hats and to avoid tearing of the delicate material of the sweat bands, comprises a tension bar 55 mounted 105 for reciprocation in guides in the machine frame so as to move parallel to and at one side of the needle bar 5. It is actuated by an eccentric 56 operating in a yoke 57 attached to the tension bar 55. As shown clearly in 110 Fig. 7 the eccentric 56 imparts to the tension bar 55 a throw somewhat more than half the throw of the needle bar 5 actuated by the cam 6. The timing of the eccentric 56 is preferably so arranged as to be slightly behind the eccentric 6, but this timing is under control and may be varied to meet varying requirements, and, as shown, in order that the eccentric 56 may be accurately positioned and adjusted so as to give the best timing 115 120 for the tension control, it is adjustably secured to the shaft 2 by means of a set screw 58.

125 In threading the machine the thread is passed from the spool 59 through the guide 60 and through openings 61 in lugs or projections 62 upon the face of the machine frame. Between the projections 62 it passes across the front of the upwardly projecting portion 63 of the tension bar 55 and 130

thence to its connections on the needle bar 5 and to the needle N. The effect of this arrangement is shown in the different positions of the parts illustrated in Figs. 9, 10, 11 and 12. In Fig. 9 the needle N is shown in the position of its farthest advance with the looper in position to take the loop about to be formed. Here the tension bar 55 is advanced to its position of greatest advance, or nearly so, and the thread has been drawn up so that the completed stitch has been made snug. In Fig. 10 the needle N has receded somewhat from the loop and the point 9^b of the looper has entered the loop and has begun drawing out the loop for making the next stitch. The tension bar 55 has also receded somewhat leaving the thread slack for making the loop. In Fig. 11 the loop is completely formed and the needle has advanced somewhat on its subsequent advance stroke and is shown passing through the loop, and the slack provided by the tension bar 55 has been taken up in the formation of the loop. In Fig. 12 the loop has passed off the back 9^a of the looper 9 and the needle has advanced to complete the stitch, and the joint action of the advance of the needle and the tension bar 55 has drawn up the thread of the completed stitch so as to make the same properly snug and tight. As will be seen, the tightening of the thread all takes place on the inner side of the seam, that is to say, next to the machine frame or casing, and this tightening also takes place while the needle is in the material being sewed and the needle thus holds the material firm and prevents tearing; and the pull of the looper 9 on the thread to form the loop occurs while the thread is slack and plenty of loose thread is available for forming the loop so that there is no tendency to tear the material by pull on the thread when the needle is disengaged therefrom.

The means for guiding the sweat band and the cord guide are shown clearly in Fig. 4. The needle guide bar 58' is secured to the arm 47, which carries the wheel 46 journaled on the journal 59', by any convenient means as by the screw 59^a and is provided with a central longitudinal slot 60' which the needle enters and which guides the needle in its movement. This slot divides the upper portion of the needle guide bar 58' into two parts, 61' and 62'; the part 62' of the needle guide bar which is engaged first by the hat and sweat band is provided with a projecting lip 63' for affording an upper edge guide to the sweat band and is recessed on the bottom at 64 to guide the inner edge of the sweat band in its passage through the machine. The inner wall 65 of this recess 64 is substantially a continuation of the outer face 46^a of the presser wheel 46, so that the sweat band is held firmly in place and kept

straight at and near its inner edge. The cord guide 66 is secured to a sweat band guide carrying plate 67 which is also secured in place as by the screw 59^a to the arm 47. The sweat band guide carrying plate 67 is formed of thin spring material and is free to give somewhat to upward pressure. It is provided with a downward extension 68, which may be made in a separate piece, and an inner wall 69 which operates with the lip 63' and the inner wall 65 of the recess 64 and the face 46^a of the wheel 46 to provide complete guiding means for the sweat band. The plate 67 also extends toward the machine frame at 70 to assist the feed wheel 45 in guiding and holding down the hat during the sewing operation and the forward end thereof 71 is rounded upwardly so as to make it easy for the hat and sweat band to be introduced and fed into the machine.

The operation of the machine described is as follows: The machine having been stopped with the needle and looper in retracted position where both are back of the edge of the feed wheel 45, and are therefore out of the way, the latch 53^a is turned so as to unlock the swinging arm 47 and the arm 47 is pulled forwardly so as to move the presser wheel 46 away from the feed wheel 45, the post 49 on which the arm 47 is pivoted moving forward substantially parallel to itself upon its link support and against the opposed pull of the spring 53 to permit the forward bodily movement of the wheel 46 and arm 47. The arm 47 is then swung upwardly on its pivot 48, and, as a slight friction is provided at this pivoting point, the arm 47 and the attached parts will remain tilted upwardly and out of the way, as is clearly shown in Fig. 5. As the presser wheel 46, when the parts are in working position, serves to support the frame 39 and the ring 35, on which the hat rests, against the feed wheel 45, when the presser wheel 46 has been moved upward and out of the way, the frame 39 will be free to be tilted outward on the pivot 41 by the operator applying pressure thereon against the action of the supporting spring 44^a. The frame 39 being drawn forward by the operator against the action of the spring 44^a, the parts are entirely separated at the sewing point, and a hat being first inverted may readily be placed upon the supporting ring 35 with the crown entering the opening therein and the rim resting upon the tapered supporting surface 36, the top edge of the supporting ring contacting with the hat at the bend between the crown and the rim. It is not necessary that special size rings 35 be provided for different size hats, as it is important only that the hat be in close contact with the supporting ring at the sewing point, and it need not contact closely there-

with all the way around the ring, as will be understood. One end of the sweat band to be sewed in the hat is then brought into position with its edge substantially flush with the bent over surface of the hat at the bend on top of the ring 35, the end of the sweat band being opposite or substantially opposite the needle. The frame 39 and ring 35 are then brought up against the feed wheel 45 which rests upon the hat rim, contacting with the under surface thereof (which is on top, the hat having been inverted) near the bend where the sewing operation is to take place, and the spring 44^a supports it lightly in this position. When the parts have been arranged as described, the operator temporarily holding the sweat band in position, swings the wheel 46 and arm 47 downward on the pivot 48 and holds the arm 47 forward against the tension of the spring 53 and then moves or pushes the same straight back, the post 49 moving substantially parallel to itself as has been described, and the edge of the presser wheel 46 resting against the inside of the sweat band, pressing the sweat band, the hat and the supporting ring 35 against the feed wheel 45 with sufficient firmness to insure a proper feeding action, and when the parts are positioned in this manner the latch 53^a is locked over the arm 47 to hold it down and retain it in the proper adjusted position. As the presser wheel 46 is supported so as to swing on its pivot 48 and also so as to move straight in and out, the guide wall 69 may readily be brought into the proper guiding relation to the sweat band and hat rim as the presser wheel 46 and arm 47 and the guide members 68, 69 and carrying plate 67 borne thereby are depressed, and the parts brought into sewing position. If desired, the operator can place the end of the sweat band a little back of the sewing point and after the parts have been positioned as above described, can advance it slightly toward the sewing point so that the edge of the sweat band will assume the proper position between the guiding surfaces, which consist of the edge 46^a of the presser wheel and the lower face 64^a of the projecting lip 63' and the inner face 65 of the recess 64 and the wall 69 of the guide plate 68.

The hat and sweat band having been positioned in the machine in the manner just described, and the cord which is preferably to be sewed between the sweat band and hat, having been introduced in its proper relative position, being fed through the cord guide 66 provided for that purpose, the machine may be set into operation, the frame 39 having first been properly adjusted in a vertical direction by means of the screw 42 so that the needle will obtain the proper amount of "bite" on the material of the hat adjacent to the band to secure the sweat band firmly in place and at the same time not to penetrate through to the upper surface of the hat. As the machine is operated the needle N will pass through a portion of the exposed edge of the hat at the bend and under the cord C and through the upper edge of the sweat band S drawing the thread with it, and when the needle has reached its position of farthest advance and has receded slightly so as to form a loop, the point 9^b of the looper will enter the loop and draw it upward and to one side and backward over the parts being sewed and then downward and to the opposite side of the needle, in order that the needle may pass through the loop for forming the next stitch, when the thread will pass off the heel 9^a of the looper, in the manner common in devices of this character. The tension bar 55 advancing with the needle or slightly behind it, will draw out a length of thread sufficient for enabling the loop to be readily formed without tension, the slack provided by its advance being taken up by the looper in forming the loop. With this arrangement there is substantially no pull upon the parts being sewed during the formation of the loop, as the looper has only to draw out a slack length of thread requiring practically no pull. As the needle advances during the subsequent stroke and while it is in contact with the parts being sewed, the joint action of the advancing needle and the tension bar 55 results in pulling up the excess length of thread contained in the loop, and brings the stitch when completed to the proper degree of snugness to secure the sweat band to the hat so that it is properly sewed in place and with the desired tightness of stitch and at the same time without any tearing action. As already stated, the cam 56 is capable of adjustment on the shaft 2 by means of the set screw 58, so that it may be set in such timing relation to the needle bar cam 6 as that its operation will result in securing the effects which have been described.

It will be seen that as the machine is operated the feed wheel 45, in addition to its feeding action in advancing the parts to be sewed the necessary distance for the formation of each stitch, also serves to hold the hat rim down and to maintain it in contact with the downwardly tapering outer surface of the supporting ring 35, so that the seam will accurately follow the turned over edge of the hat between the crown and rim. The operator may place his left hand upon the hat where it rests on the ring 35 somewhat in advance of the guide plate 67 and if this is done and the sweat band held lightly up so that it will not drop below the guide plate 67, a substantially perfect seam will be readily secured. When the seam has been sewed entirely around the hat the parts are disengaged in the manner already described,

the thread and cord are cut off, and the operation which has been described is repeated for each hat, although it will not be necessary to adjust the device for height unless hats of different thicknesses are to be operated upon. The machine described is altogether positive in its action, the hat and sweat band and cord are firmly guided and supported at the sewing point, and the disengagement is readily accomplished and is thoroughly complete, and plenty of room is provided to enable the easy insertion and removal of hats and sweat bands, and with a machine as described the operation of sewing sweat bands into hats may be effectively and quickly performed, the operator being able to turn out good work rapidly and without any considerable exertion or close attention.

20 Having now described our invention, we claim:

1. In a hat sweat sewing machine, sewing mechanism including a needle, hat supporting means, a presser wheel normally received within a hat supported by said supporting means and movable toward and away from the sewing mechanism, and a needle guide and a separate sweat band guide movable with said presser wheel, said sweat band guide being capable of limited movement with respect to said needle guide, substantially as set forth.

2. In a hat sweat sewing machine, sewing mechanism including a needle, hat supporting means, a presser wheel normally received within a hat supported by said supporting means and movable toward and away from the sewing mechanism, a needle guide and a separate sweat band guide movable with said presser wheel, said sweat band guide being capable of limited movement with respect to said needle guide, and a cord guide carried by said sweat band guide, substantially as set forth.

3. In a hat sweat sewing machine, sewing mechanism including a needle, hat supporting means, means for holding said hat supporting means in position during the sewing operation, a needle guide and a separate sweat band guide carried by said holding means, said sweat band guide being capable of limited movement with respect to said needle guide, and a cord guide carried by the sweat band guide, substantially as set forth.

4. In a device of the class described, the combination of a movable frame, rollers on said frame, a substantially ring shaped member having a downwardly tapering outer surface and provided with a trackway resting on said rollers, and means for sewing a sweat band to a hat when supported in said ring shaped member, substantially as and for the purposes set forth.

5. In a device of the class described, the combination of a vertically adjustable frame, rollers rotatably mounted on said frame, a substantially ring shaped hat supporting member provided with a trackway and free to rotate on said rollers, and means for sewing a sweat band to a hat when supported in said ring shaped member, substantially as and for the purposes set forth.

6. In a device of the class described, the combination of a framework provided with rollers, a continuous substantially ring shaped member for receiving a hat and free to rotate on said rollers and having a downwardly tapering outer surface, means for vertically adjusting said frame and the ring and hat carried thereby, and substantially horizontally operated means for sewing a sweat band to a hat supported in said ring shaped member, substantially as and for the purposes set forth.

7. In a device of the class described, the combination of a substantially ring shaped member for receiving a hat in inverted position and having a downwardly tapering outer surface upon which the rim of the hat rests, a horizontally arranged feed wheel having an inwardly tapering corrugated lower surface adapted to contact with the hat rim where it rests upon the ring shaped member, means for supporting said ring shaped member with the hat in contact with said feed wheel, means for imparting intermittent rotation to said feed wheel, and means for sewing a sweat band to a hat supported by said ring shaped member, substantially as and for the purposes set forth.

8. In a device of the class described, the combination of a substantially ring shaped member for receiving a hat in inverted position and having a downwardly tapering outer surface upon which the rim of the hat rests, supporting means upon which said ring shaped member is freely rotatable in a substantially horizontal plane, and means for sewing a sweat band to a hat supported by said ring shaped member, substantially as and for the purposes set forth.

9. In a device of the class described, the combination of a substantially ring shaped member having a central opening for receiving the crown of a hat placed in inverted position and provided with a downwardly tapering outer surface upon which the rim of the hat rests, feeding means applied upon the rim of the hat where it rests against the downwardly tapering outer surface, and means for sewing a sweat band to a hat at the bend between the crown and the rim, substantially as and for the purposes set forth.

10. In a device of the class described, the combination of a substantially ring shaped member provided with a central opening to

- receive the crown of a hat placed in inverted position and provided with a downwardly tapering outer surface upon which the rim of the hat rests, feeding means applied to the rim of the hat where it rests on said downwardly tapering outer surface, means applied within the opening in said ring shaped member for forcing said member and the hat placed thereon against said feeding means, and means for sewing a sweat band in said hat when so supported, substantially as and for the purposes set forth.
11. In a device of the class described, the combination of a substantially ring shaped member provided with a central opening for receiving the crown of a hat placed in inverted position and provided with a downwardly tapering outer surface upon which the rim of the hat rests, intermittent feeding means applied to the rim of the hat where it rests on the downwardly tapering outer surface of said ring shaped member, a presser wheel resiliently forced against the interior of said ring for pressing said ring and hat carried thereby against the said feeding mechanism, and chain stitch forming mechanism for sewing a sweat band to a hat so supported, substantially as and for the purposes set forth.
12. In a device of the class described, the combination of means freely rotatable in a substantially horizontal plane for supporting a hat and provided with a downwardly tapering outer surface upon which the rim of the hat rests, feeding means contacting with the hat rim where it rests on said downwardly tapering outer surface and arranged so as to be rotated in a substantially horizontal plane, means for pressing said supporting means and hat against said feeding means and means for sewing a sweat band in a hat supported by said supporting means, substantially as and for the purposes set forth.
13. In a device of the class described, the combination of a substantially ring shaped member provided with a central opening to receive the crown of a hat placed in inverted position and provided with a downwardly tapering outer surface upon which the rim of the hat rests, feeding means applied to the rim of the hat where it rests on said downwardly tapering outer surface, and means for sewing a sweat band to a hat when so supported, substantially as and for the purposes set forth.
14. In a device of the class described, the combination of freely rotatable horizontally arranged supporting means for receiving a hat in inverted position and having a continuous downwardly tapering outer surface upon which the rim of the hat rests, feeding means applied to the under surface of the hat rim adjacent to the bend between the

crown and rim and against which the rim of the hat is supported by the said downwardly tapering outer surface of said supporting means, and means for sewing a sweat band to a hat so supported, substantially as and for the purposes set forth.

15. In a device of the class described, the combination of a freely rotatable substantially ring shaped member having a central opening for receiving the crown of a hat in inverted position and provided with a downwardly tapering outer surface upon which the rim of the hat rests, feeding means applied to the hat rim where it rests upon said downwardly tapering outer surface, a guide for guiding a sweat band in place, and means for sewing the sweat band to a hat so supported, substantially as and for the purposes set forth.

16. In a device of the class described, the combination of a freely rotatable substantially ring shaped member having a central opening for receiving the crown of a hat placed in inverted position and provided with a downwardly tapering outer surface on which the rim of the hat rests, means applied to the hat rim where it rests on said downwardly tapering outer surface for feeding the hat and supporting means, a guide for guiding a sweat band in place, resilient means for pressing the ring shaped member and hat carried thereby in contact with the feeding means, and means for sewing the sweat band to a hat when so supported, substantially as and for the purposes set forth.

17. In a device of the class described, the combination of a freely rotatable substantially ring shaped member having a central opening for receiving the crown of a hat placed in inverted position and provided with a downwardly tapering outer surface on which the rim of the hat rests, means applied to the hat rim where it rests on said downwardly tapering outer surface for feeding the hat and supporting means, a pivoted arm, a freely rotatable presser wheel carried by said arm and means for locking said pivoted arm and presser wheel so that the said presser wheel presses the said ring shaped member and hat against said feeding mechanism, and means for sewing a sweat band to a hat, substantially as and for the purposes set forth.

18. In a device of the class described, the combination of a substantially ring shaped member having a central opening for receiving the crown of a hat in inverted position and provided with a downwardly tapering outer surface upon which the rim of the hat rests, a horizontally arranged intermittently rotating feed wheel contacting with the rim of the hat where it rests upon said downwardly tapering outer surface of the supporting ring, a resiliently retracted pivoted

arm, a rotatable presser wheel carried by said arm, a sweat band guide and a cord guide carried by said arm, said presser wheel operating to press said ring shaped member and hat supported thereby against said feeding mechanism, and a stitch forming mechanism for sewing a sweat band to a hat supported in said ring shaped member, substantially as and for the purposes set forth.

19. In a device of the class described, the combination of a freely rotatable substantially ring shaped member having a central opening for receiving the crown of a hat in inverted position and provided with a downwardly tapering outer surface upon which the rim of the hat rests, a horizontally arranged intermittently rotating feed wheel contacting with the rim of the hat where it rests upon said downwardly tapering outer surface of the supporting ring, stitch forming mechanism, and means for pressing said hat supporting means into contact with said feeding means comprising a presser wheel, a pivoted arm upon which said presser wheel is carried, a post or rod upon which said arm is pivoted and so connected to the machine frame as to be movable parallel to itself and a spring for moving said post or rod toward the machine frame and forcing said presser wheel against the hat supporting means, substantially as and for the purposes set forth.

20. In a device of the class described, the combination of a substantially ring shaped member having a central opening for receiving the crown of a hat in inverted position and having a downwardly tapering outer surface upon which the rim of the hat rests and also provided with a trackway on its under surface, a pivoted vertically adjustable spring pressed frame provided with rollers upon which said ring shaped member is freely rotatable, a horizontally arranged intermittently rotatable feed wheel having an inwardly tapering lower surface contacting with the rim of the hat where it rests on the downwardly tapering outer surface of the supporting ring shaped member, a pivoted spring retracted arm, a latch for said arm, a guide carried by said arm for guiding a sweat band in place in said hat, a rotatable wheel carried by said arm and contacting with the interior of the hat and pressing said sweat band and hat and supporting ring against said feed wheel, a cord guide carried by said sweat band guide, a loop-stitch forming mechanism for sewing the sweat band and cord in place in the hat, and a tension device providing slack thread for forming the loop and thereby preventing the tearing of the hat in the sewing operation, substantially as and for the purposes set forth.

21. In a hat sweat sewing machine, sew-

ing mechanism including a needle, movable hat supporting means conforming substantially to the form of a hat so as to support the hat during the sewing operation without substantial deformation, means for holding said hat supporting means in position during the sewing operation, and a sweat band guide carried by said holding means, substantially as set forth.

22. In a hat sweat sewing machine, stitch forming means, a movable hat support conforming substantially to the form of a hat so as to support the same during the sewing operation without substantial deformation, rotatable means for holding said support in place during the sewing operation, a bodily movable member to which said holding means is pivotally connected, said holding means being movable upon movement of said member bodily toward and away from the stitch forming means, substantially as set forth.

23. In a hat sweat sewing machine, a hat support provided with an opening therein, and means normally received within the opening in said hat support for pressing against the said hat support during the sewing operation, said means being rotatable, turnable outwardly and upwardly on a pivot located above the hat support and at substantially the front of the machine, and mounted to have a movement of translation, substantially as set forth.

24. In a hat sweat sewing machine, stitch forming means, movable hat supporting means conforming substantially to the form of a hat and serving to support a hat during the sewing operation without substantial deformation, and a presser wheel for holding said hat supporting means in place during the sewing operation, said presser wheel being pivoted to turn on a pivot arranged above the stitch forming means, and having, in addition to such pivotal movement, a movement of translation toward and away from the stitch forming means, substantially as set forth.

25. In a hat sweat sewing machine, stitch forming means, feeding means, movable hat supporting means conforming substantially to the form of a hat and serving to support a hat during the sewing operation without substantial deformation, means for holding said hat supporting means up to said feeding means and comprising a pivoted and bodily movable arm, and a latch for locking said arm against pivotal movement substantially as set forth.

26. In a hat sweat sewing machine, stitch forming means, a ring-shaped member provided with a downwardly tapering outer surface, feeding means coacting therewith, a presser wheel within said ring-shaped member for holding it against said feed-

ing means, an arm on which said presser wheel is carried, said arm being mounted to turn pivotally on an axle above the stitch forming mechanism, and said arm being mounted so as to be movable with said presser wheel carried thereby substantially parallel to itself, substantially as set forth.

27. In a hat sweat sewing machine, a hat support, a bodily movable member, an arm pivoted thereto, revoluble means on said arm for holding said hat support in position, and means for locking said arm against pivotal movement with respect to said bodily movable member, substantially as set forth.

28. In a hat sweat sewing machine, stitch forming means, a presser wheel for pressing a hat toward said stitch forming means, an arm pivoted above said stitch forming means and at substantially the front of the machine to turn outwardly and upwardly upon which said presser wheel is revolubly supported, and means applied to said arm for holding said presser wheel against the hat, substantially as set forth.

29. In a hat sweat sewing machine, stitch forming means, a presser wheel, an arm pivoted above the stitch forming means upon which said presser wheel is revolubly

supported, and a bodily movable member to 30 which said arm is pivoted, substantially as set forth.

30. In a hat sweat sewing machine, stitch forming means, a presser wheel for pressing a hat toward said stitch forming means, a pivoted arm on which said presser wheel is revolubly mounted, a bodily movable member to which said arm is pivoted, and spring retracting means connected with said member, substantially as set forth. 35 40

31. In a hat sweat sewing machine, stitch forming means, a presser wheel for pressing a hat toward the stitch forming means, a bodily movable member, spring means for holding said member in retracted position, 45 an arm pivoted to said member, said presser wheel being revolubly mounted on said arm, and a latch on said member for locking said arm in position, substantially as set forth.

In witness whereof we have signed this 50 specification in the presence of two subscribing witnesses, this 8th day of April, 1913.

WILLIAM A. KNIGHT.
LEO BAUER.
